Mitchell Waller

UNITED STATES PATENT OFFICE.

CLARENCE D. PLATT, OF BRIDGEPORT, CONNECTICUT.

PANEL-BOARD.

1,321,144.

Specification of Letters Patent. Patented Nov. 11, 1919.

Application filed May 18, 1918. Serial No. 235,242.

To all whom it may concern:

Be it known that I, CLARENCE D. PLATT, a citizen of the United States of America, residing at Bridgeport, Connecticut, have invented a new and useful Panel-Board, of which the following is a specification.

My invention relates to panel boards of the so-called sectional or built up type.

The objects of the invention are to provide a suitable cover for panel boards of this sectional or extensible construction and to provide a grounding connection which will insure proper grounding of the cover.

According to the invention, each panel unit is provided with a cover section and these cover sections are formed with up-turned flanges which coöperate when the cover sections are assembled to form a lateral inclosure about the sectional cover. Proper grounding of the various cover sections is insured by securing said cover sections in place by screws or other fastening devices which make electrical connection with a common ground bar.

Various other features of the invention and details of construction will appear as the specification proceeds.

The accompanying drawings illustrate the invention embodied in one of its practical commercial forms but it is to be understood that changes and modifications may be made without departure from the true spirit and scope of the invention.

In said drawings:

35 Figure 1, is a broken front view of the panel board.

Fig. 2, is a longitudinal sectional view of the same, taken substantially on the plane of the line 2—2 of Fig. 1.

40 Fig. 3 is a broken perspective view of the sectional cover as applied to the assembled panel units.

Figs. 4 and 5 are detail views of the blanks from which the cover sections are formed.

45 The structure of the panel units will vary to suit different requirements. In the illustration the panel units are shown in the form of push button switches 8, said units being assembled in side by side relation on sub bases or base sections 7, to form a built up panel of the required character and capacity.

These panel units are provided each with a laterally projecting yoke or strap 9. The 55 straps of the several units are secured to a

common ground bar 10 as by means of the screws 11. The ground bar may be provided with a suitable terminal, such as indicated at 12 for connection with a grounding wire, or this ground bar may, if desired, be formed with a rearward extension 13 which may be in direct electrical connection with the inclosing box 14 as by means of the screw 15.

In the present construction, two sets of panel units are illustrated, those at the right being shown connected with a straight ground bar having the terminal 12 for connection of a wire therewith, those at the left being shown connected with a ground bar 70 formed with a rearward grounding extension directly connected with the panel box.

The cover for the panel units is as previously stated, made in sections, the cover sections 16 for the upper and lower end panel units being constructed with up-turned end flanges 17 and with an up-turned side flange 18, the cover sections 19 for the intermediate panel units being formed with up-turned end flanges 20, said flanges coöperating as 80 shown to form an inclosure about the edges of the sectional cover and hence about the built up panel units. The front 21 of the panel cabinet is usually provided with an opening therein corresponding to this lateral inclosure and this opening may be provided with a door such as indicated at 22.

The several cover sections are secured in place by devices such as the screws 23 which take into the screw seats 24 provided in the 90 yokes or straps 9. Hence, in fastening each cover section in place it is by that very act automatically grounded or electrically connected with the grounding bar.

The invention it will be seen, provides a 95 cover which is extensible in accordance with the building up of the panel board and which no matter how extended will always provide an inclosure about the exposed portions of the panel. Also the possibility of 100 neglecting or failing to properly ground the sectional cover is done away with because of the fact that the simple act of securing the cover sections in place automatically connects them in proper ground- 105 ing relation.

I claim:

1. In a panel board, panel units assembled side by side into a built up panel board of the required size, a cover section over each 110

of said panel units and having angularly up-turned edge flanges coöperating to form an inclosure about the cover sections.

2. In a panel board, panel units assembled side by side into a built up panel board of the required size, cover sections over the end panel units, each having the ends and one side edge thereof provided

with an up-turned flange and cover sections over the intermediate panel units having end flanges coöperating to form with the end and side flanges of the end cover sections a lateral inclosure about said cover sections. 10

CLARENCE D. PLATT.
